Primary Examiner — Philip S Hyder*(74) Attorney, Agent, or Firm* — Fulwider Patton LLP(57) **CLAIM**

I, claim the ornamental design for an internal winding spool, as shown and described.

DESCRIPTION

FIG. 1 is a perspective view showing my new design;

FIG. 2 is a left hand end view thereof;

FIG. 3 is a top view thereof;

FIG. 4 is a bottom view thereof;

FIG. 5 is a front thereof; and,

FIG. 6 is a back view thereof.

The broken lines represent portions of the structure that form no part of the claim.

1 Claim, 3 Drawing Sheets
